UNITED STATES PATENT OFFICE.

CONRAD HOFMANN, OF BERIRK SCHLUCKENAU, CZECHOSLOVAKIA.

CHILD'S ROCKING-HORSE.

Application filed March 25, 1926, Serial No. 97,427, and in Czechoslovakia January 24, 1925.

This invention relates to a travelling rocking horse which may be used for ordinary rocking as well as for alternate forward and backward travel.

5 An embodiment of the invention is illustrated in the accompanying drawing in which:

Fig. 1 is a front elevation;

Fig. 2 a longitudinal section through the 10 horse in rocking position;

Fig. 3 is a cross section;

Fig. 4 a longitudinal section through the horse in the position in which it is adapted to travel forward,

15 Fig. 5 a longitudinal section in the position in which it is adapted to travel rearwards.

In the drawing 1 indicates the neck of the horse and its head, 2 the handle adapted to 20 be gripped by the rider, 3 the breast-plate, 4 the sides of the body, 5 the rear part, 6 the tail, 7 the back serving as seat for the rider, 8 the front saddle support, and 9 the rear saddle support.

25 The body of the horse is hollow and is open on the lower side and contains the detent and movement-producing mechanism.

The two front legs 10 are secured to a cross 30 bar 11, at each side of which a rocker 12 is fixed. In the upper part the front legs 10, which are connected with one another by a rod 13 are suspended by means of a spindle 14 fixed in the sides 4 of the body.

The two hind legs 15 are fixed on a cross 35 bar 16, which has at each end a rocker 17. The hind pair of legs are, like the front pair, connected with one another by a rod 18 and are freely movable on a spindle 19 fixed in the sides 4 of the body.

40 The movement imparting and detent mechanism accommodated in the body consists of the upper two bars 20 which are carried in bores in both ends of the two spindles 14 and 19. In the middle between the two bars 20 45 two locking levers 23 and 24 are freely suspended on bolts 21 and 22, secured in the bars 20, said locking levers, which are spread asunder by the action of a spring 25, serving to lock in their positions the front

50 and hind pair of legs. A detent 26 is arranged beneath the locking levers and has at the middle a dove-tailed recess with which engage the lower ends of the locking levers 23 and 24. This detent element 26 is suspended, on the one hand, by means of a pivoted lever 27 on the spindle 14, and on the

other hand, by means of a pivoted arm 28 on the spindle 19. An extension 29 at the upper end of the detent lever 27 forms a handle by means of which the detent lever 27 which is oscillatable on a sector 30 between the abutments on said sector, and through this detent lever the detent element 26 can be moved backwards. By this displacement the locking hooks 23 and 24 are pressed away 60 from or towards the rods 13 and 18 so that the front and hind pairs of legs are alternately locked or released for movement.

The foot supports or stirrups 31 are fixed each on a vertical arm 32 said arms, which 70 are fixed by means of screws 33 in the sides of the body, being enlarged at the upper ends to form each an abutment for the legs. On each screw 33 a forkshaped blade spring 34 is fixed the free ends of which, pressing 75 upon the two rods 13 and 18 of the front and hind pair of legs, cause the movement of the front legs in forward direction and the movement of the hind legs in rearward direction.

80 The end walls of the body have felt covers 35 designed to deaden the noise caused by the legs striking against these end plates.

The operation for making the rocking horse ready for rocking is as follows. The 85 detent lever 27 and the detent element 26 connected with the same are brought into the central position by moving the handle 29 onto the centre of the segment 30. The locking hooks 23 and 24 are pressed asunder 90 by means of the spring 25, the locking levers adopt the position shown in Fig. 2 bearing against the ends of the dove-tailed recess in the element 26. The rods 13 and 18 of the front and hind legs will therefore, if 95 at the rocking movement the front and hind legs butt against the enlarged upper ends of the vertical pieces 32, engage with the notches of said locking hooks so that both pairs of legs are locked against the vertical pieces 32. The front and the hind pairs of legs and the rockers of the same remain locked in this position and the horse rocks back and forward on the spot without moving along the floor.

100 To bring the mechanism into the position shown in Fig. 4 for forward travelling the operation is as follows:—

The handle 29 of the detent lever 27 is depressed into the extreme position on the segment 30, whereby the detent element 26 is 110 shifted backward so that the locking hook

23 is pushed away from the rod 18 which connects the front legs, so that these front legs and their rockers are released and can oscillate in forward direction under the pressure of the corresponding arm of the blade spring 34. The locking hook for the hind legs is not affected thereby so that these hind legs remain pressed onto the central piece 32.

10 If the horse is being rocked in forward direction it advances by a distance equal to the distance between the two rockers 12 and 17 and the lower ends of the rockers 12 of the front legs will first come in contact with 15 the floor whereupon the hind part of the body is raised together with the locked hind legs and their rockers. If the forwardly directed rocking movement continues the hind part of the body is oscillated through 20 the action of the weight of the rider around the spindle 19 and towards the front legs, until the vertical piece 32 comes in contact with the front legs and the front and rear rockers stand close together, the springs 34 25 being compressed and put under tension.

At the subsequent rearward swing the legs and rockers remain close together until the front rockers 12 have adopted the position in which they can lift off the floor. At this 30 moment the front legs are again moved forward under the pressure of the springs 34 and the same operation is repeated as described above. The horse travels forward at one rocking movement by a distance equal 35 to the distance between the front and rear rockers.

To bring the horse into the position shown in Fig. 5 for backward movement from the rocking position the operation is as 40 follows:—

The handle 29 of the detent lever 27 is pulled up so that it comes into contact with the upper abutment on segment 30 whereby the detent element 26 is shifted in forward 45 direction and pushes the locking hook 24 away from the rod 18 connecting the hind legs, so that the hind legs together with their rockers are free and are pushed in rearward direction by the action of the springs 34 and 50 become freely movable. The front legs are not affected thereby and remain pressed against the vertical elements 32. At the rocking movement in rearward direction the horse is moved a distance equal to the distance 55 between the two rockers 12 and 17. The lower ends of the rear rockers 17 come first into contact with the floor, the front part of the body being raised in the same swinging movement together with its locked 60 front legs and their rockers. When the rearward swinging movement continues, the front part of the body is oscillated by the action of the weight of the rider around the spindle 19 and pressed against the hind legs 65 until the vertical piece 32 strikes against

these hind legs, so that the two rear and front rockers stand close together, the springs 34 being compressed and put under tension. At the subsequent forward rocking movement the legs and rockers remain 70 close together until the rear rockers 17 have arrived at the point at which they can lift off the floor. At this moment the hind legs are again forced backwards by the pressure of the springs 34 and the same operation is 75 repeated. The rocking horse moves therefore rearwards in one swing a distance equal to the distance between the front and rear rockers.

I claim:

1. A travelling rocking horse comprising in combination with the hollow body of the horse open in the lower surface, a spindle in the front part of said body, a pair of front legs pivotally mounted at the front corner of the upper end on said spindle, a rod connecting the one with the other the legs of the front pair, a spindle in the rear part of said body, a pair of hind legs pivotally mounted at the front corner of the upper end on said rear spindle, a rod rigidly connecting the one with the other the two legs of the hind pair, rockers under said front legs, rockers under said hind legs, spreading springs fixed between the pairs of legs and acting upon said rods for pushing the front legs and hind legs away from one another, locking hooks oscillatably suspended on said spindles and having each a notch designed to receive said cross rods of the pairs of legs, a central vertical piece having a large top end against which said legs are pressed when said rods are caught by said locking levers, and a horizontal detent element for holding said locking hooks in the locking position.

2. A travelling rocking horse comprising in combination with the hollow body of the horse open in the lower surface, a spindle in the front part of said body, a pair of front legs pivotally mounted at the front corner of the upper end on said spindle, a rod connecting the one with the other the legs of the front pair, a spindle in the rear part of said body, a pair of hind legs pivotally mounted at the front corner of the upper end on said rear spindle, a rod rigidly connecting the one with the other the two legs of the hind pair, rockers under said front legs, rockers under said hind legs, spreading springs fixed between the pairs of legs and acting upon said rods for pushing the front legs and hind legs away from one another, locking hooks oscillatably suspended on said spindles and having each a notch designed to receive said cross rods of the pairs of legs, a central vertical piece having a large top end against which said legs are pressed when said rods are caught by said locking levers, a horizontal detent

element for holding said locking hooks in the locking position and having a recess at the middle; spreading springs for spreading asunder said locking hooks so that their ends bear against the end walls of said recess, a hand lever for moving said detent element forward or backward to release the corresponding pair of legs which are then moved forward or backward by the action of said spreading springs and the rocking horse in rocking moves forward or backward.

In testimony whereof I have signed my name to this specification.

CONRAD HOFMANN.
